DESIGN FOR A DOLL

Florence A. Sherman, New York, N. Y.

Application September 13, 1939, Serial No. 87,174

Term of patent 7 years

To all whom it may concern:

Be it known that I, Florence A. Sherman, a citizen of the United States, residing at New York, in the county of New York and State of New York, have invented a new, original, and ornamental Design for a Doll, of which the following is a specification, reference being had to the accompanying drawing, forming part thereof.

In the drawing:

Fig. 1 is a front view of a doll showing my new design;

Fig. 2 is a rear view thereof; and

Fig. 3 is a side view thereof.

I claim:

The ornamental design for a doll, as shown.

FLORENCE A. SHERMAN.
